DESIGN FOR A SHOE SOLE

Frank Berenstein, Chelsea, Mass., assignor to Panther-Panico Rubber Co. Inc., Chelsea, Mass., a corporation of Massachusetts

Application July 19, 1935, Serial No. 57,734

Term of patent 14 years

To all whom it may concern:

Be it known that I, Frank Berenstein, a citizen of the United States, residing at Chelsea in the county of Suffolk, Commonwealth of Massachusetts, have invented a new, original, and ornamental Design for a Shoe Sole, of which the following is a specification, reference being had to the accompanying drawing, forming a part thereof.

In the drawing, Fig. 1 is a plan view of a shoe sole showing my new design; and Fig. 2 is a cross-section on the line 2—2 of Fig. 1.

I claim:

The ornamental design for a shoe sole, as shown.

FRANK BERENSTEIN.
